ELECTRIC PUFF IRONER
 Helen Wilke, Marcellus, Mich.
 (1004 W. Broadway St., Mishawaka, Ind.)
 Filed Jan. 18, 1961, Ser. No. 83,420
 5 Claims. (Cl. 219—21)

The present invention relates to electric ironers, and more particularly to ironers for portions of garments such as sleeves, ruffles, puffs, and lace, which cannot be conveniently ironed by the conventional hand iron.

It is a principal object of the present invention to provide an ironer for puffs, lace, ruffles, and the like, which is shaped for the greatest possible ease and convenience in ironing these special portions of garments with simple motions of the hand and wrist.

A further object of this invention is to provide an electric puff ironer which gives a thermostatic control over the heating of the ironing surface within a small temperature range and which heats evenly over the whole ironing surface.

Another object of the invention is to provide a puff ironer with a thermostatic control in which the thermostat for temperature control will not catch on the clothing being ironed and not interfere with the ironing operation, and which is yet conveniently within reach of the person ironing.

It is an additional object of the invention to provide an electric puff ironer which is attractive, small and easily portable, and which will clamp tightly on an ironing board or table without danger of slipping or turning.

Still another object is to provide an ironer which is simple and rugged in material and design, easily and cheaply manufactured and readily repaired when necessary.

Additional objects and advantages will become apparent from the following description and accompanying drawings, wherein:

FIGURE 1 is a perspective view of an ironing board with my ironer mounted thereon;

FIGURE 2 is a side elevational view of a portion of the ironer, showing the thermostatic control;

FIGURE 3 is a fragmentary cross sectional view of the ironer taken along line 3—3 of FIGURE 2;

FIGURE 4 is a vertical cross sectional view of the ironer, showing the wiring system of the ironer;

FIGURE 5 is a top plan view of the ironer; and

FIGURE 6 is a cross sectional view of one of the clamps for holding the ironer on a board or table, taken along line 6—6 of FIGURE 5.

Referring more specifically to the drawings, numeral 10 designates my ironer, mounted on the broad end 12 of an ironing board 14 having narrow end 16 and legs 18. Ironer 10 includes a hollow stem 20 carrying head 22 and supported by base 24, with a power cord 26 of a conventional type. Base 24 is clamped to the ironing board or other support by clamps 28 and 30.

As seen in FIGURES 2 and 3, the head 22 consists of a head plate 36 of solid metal, such as cast aluminum, connected to a hollow cup-like bottom 38 by screws 40 or the like, mounted in recesses 42 in the bottom. The head is smooth and generally dome shaped, with rounded corners designed to facilitate ironing thereon. The bottom, which may be made of any suitable metal or of a heat resistant plastic, contains a central hole 43 which is threaded in order that the bottom 38 may be screwed onto the threaded top 44 of stem 20, thus producing a mechanically rigid unit. Within head 22 a thermostat 50 is attached to head plate 36 with a temperature control crank 52 extending downwardly into the stem 20. The end of crank 52 is moved by a tongue 54 of a ring 56, made of plastic, metal, or the like, the ring turning on shoulder

2

58 of stem 20 with tongue 54 sliding in slot 60 in the stem. In assembling the ironer, ring 56 is slid downwardly over narrow portion 62 of stem 20 with tongue 54 sliding in a slot 64 in the stem until the ring rests on shoulder 58 and the tongue registers with slot 60. A ring 66 of the same material as stem 20 is slid over narrow portion 62 to conceal slot 64 and present a smooth surface even with the surface of stem 20, and bottom 38 is then screwed into place on the upper end of the stem. In placing head 10 plate 36 on bottom 38, crank 52 or ring 56 must be turned in order that the crank end will register with the hole in tongue 54. This structure is supported on base 24, the lower end of stem 20 having an integral flange 70 resting on the top surface of the base and a threaded extension 72 below this flange projecting through a hole 74 in base 24 with a nut 76 holding the structure securely in place.

As seen in FIGURE 4, a wire 80 from power cord 26 extends to terminal 82 of a switch 84 of a conventional type mounted in base 24, and from the other terminal (not shown) of the switch, a wire 86 proceeds to terminal 88 of the thermostatic unit 50 in the head 22. From the other terminal 90 of the thermostat, a wire 92 runs to terminal 94 of heating element 96, and the remaining 25 wire 98 of cord 26 is connected to the terminal 102 of heating element 96. The power cord extends from the hollow base 24 through a hole 104 containing a rubber grommet 106. Thus, when switch 84 is closed, current will flow through wire 80, switch 84, wire 86, thermostat 50, wire 92, heating element 96, and wire 98. When the thermostat senses the iron is too hot, it breaks the circuit, while it closes the circuit whenever the iron is too cold.

Heating element 96 is preferably embedded in head plate 36, and consists of a series of loops 108 of heating wire surrounded by electrical insulation, and is so arranged that no portion of the head plate will be more than about one half of an inch from the heating wire. Thus the plate is heated evenly and quickly with a minimum of power loss. If desired, the heating element may be placed 35 in grooves in the solid head plate instead of being cast into the plate, thus facilitating the replacement of the heating element if it should burn out or otherwise become damaged.

Clamps 28 and 30 are used to mount the ironer 10 45 securely on the ironing board 14 or table top, each including a bracket 110 having a hooked end 112 and a threaded hole 114 in the other end 115. Thumb screw 116 is mounted in the hole and is tipped with a shoe 118 having a rubber or plastic pad 120 to prevent damage to the ironing board or other support. In mounting the ironer on a board or table top 14, hooked end 112 of the bracket is inserted in slot 122 of base 24 so that end 115 with thumb screw 116 is positioned below board 14, and the thumb screw is tightened to secure the ironer solidly to the board for use. The present ironing device when mounted in the foregoing manner is rigid, and permits all necessary force to be applied to the cloth being ironed without the likelihood of the device slipping or rocking.

In operation, the ironer is turned on at switch 84 and 60 the desired temperature of head plate 36 is selected by turning ring 56. This temperature is held constant within a few degrees by the action of the thermostat mounted on the bottom of the head plate. The puffs, lace, ruffles and other parts of garments are ironed by stretching them 65 across the top of the ironer and allowing the action of the heat and stretching to remove the wrinkles. For cloth which needs to be dampened, dampening may be done before the ironing, or a mist can be sprayed onto the cloth during ironing since the iron remains fixed in position. The streamlined design of the ironer head plate with the 70 relatively pointed but rounded ends allows complete wrinkle removing, while the position of the only

support, directly underneath the ironing head, allows the free use of the ironer without interference from the support. Further, the flush and smooth arrangement of the temperature control, close to the ironing head, allows ready adjustment of the temperature without interfering with the movement of the clothing being ironed, or without catching or snagging the clothing.

While only one embodiment of the present invention has been shown and described herein, various changes and modifications may be made without departing from the scope of the invention. For example, stem 20 may be made integrally with base 24, the clamps may take any convenient form, and the shape of the head 22 may be modified for various purposes.

I claim:

1. An electric ironer for puffs, lace, sleeves and the like, comprising a hollow base, a hollow straight cylindrical stem secured to said base and extending vertically therefrom, a head secured at the center of its under side to the upper end of said stem and having a generally dome shaped metal upper plate of oblong configuration, said upper plate being smooth and having bilateral symmetry with relatively pointed ends, an electrical heating element embedded in said upper plate, a thermostatic means attached to the underside of said upper plate within said head, a rotatable ring disposed around said cylindrical stem in spaced relation to said head and being substantially flush circumferentially with the external surface of said stem, and a linkage connecting said ring with said thermostat for varying the temperature maintained by said head plate.

2. In an ironer: a cylindrical stem in vertical position, a head secured at the center of its underside to the upper end of said stem and having a generally dome shaped metal upper plate of oblong configuration, said upper plate being smooth and having bilateral symmetry with relatively pointed ends, the curvature of the upper surface of said head being relatively flat and being substantially uniform on both the longitudinal and transverse axes throughout most of the length thereof, an electrical heating element secured to said upper plate, a thermostatic means adjacent the underside of said upper plate within said head, a rotatable ring disposed around said cylindrical stem and being substantially flush circumferentially with the external surface of said stem, and a linkage connecting said ring with said thermostat for varying the temperature maintained by said head plate.

3. An electric ironer for puffs, lace, sleeves, and the like, comprising a hollow base, a hollow cylindrical stem in vertical position on said base and being secured rigidly thereto, a rotatable ring of plastic material therearound mounted substantially flush circumferentially with the outside surface of said stem, a horizontal slot in said stem near the top of the stem, a tongue extending into said slot from said ring and having a vertical hole therethrough, an oblong generally dome shaped smooth ironing head with rounded ends attached at the center of its under side to the upper end of said stem, the curvature of the upper surface of said head being relatively flat and being substantially uniform on both the longitudinal and transverse axes throughout most of the length thereof, the upper portion of said head being of solid metal, a heating element embedded in said metal, and the lower portion of said head being hollow and containing a thermostat for

65

4

maintaining the temperature of the solid portion of the head within a desired range, a control linkage extending from said thermostat through the hole in said tongue for rotation with said ring, electrical connections between said heating element and said thermostat and a source of power for operating said heating element, and a clamp means for rigidly holding said ironer in position for ironing.

4. An electric ironer for puffs, lace, sleeves, and the like, comprising a hollow base, a hollow cylindrical stem being secured to said base in vertical position, a horizontal slot in said stem, a rotatable ring around said stem covering said slot and mounted substantially flush circumferentially with the outside surface of said stem, a tongue extending into said slot from said ring and being movable with the ring, an oblong generally dome shaped smooth ironing head with rounded ends attached at the center of its under side to the upper end of said stem, the curvature of the upper surface of said head being relatively flat and being substantially uniform on both the longitudinal and transverse axes throughout most of the length thereof, the upper portion of said head being of solid metal, a heating element in said upper portion, and the lower portion of said head being hollow and containing a thermostat to maintain the temperature of the upper portion of the head within a desired range, a control linkage extending from said thermostat to said tongue for rotation therewith, a source of power, and electrical connections between said heating element, thermostat and said source of power for operating said heating element within said desired range.

5. An ironer for puffs, lace, sleeves, and the like, comprising a base, a cylindrical stem vertically connected to said base and having a rotatable ring therearound spaced from the top and bottom of said stem, a generally dome shaped smooth ironing head with rounded ends attached at the center of its underside to the upper end of said stem, the curvature of the upper surface of said head being relatively flat and being substantially uniform on both the longitudinal and transverse axes throughout most of the length thereof, the upper portion of said head being solid with a heating element in said head in close proximity to said upper portion, and the lower portion of said head being hollow and containing a thermostat for regulating the temperature of said upper portion, a control linkage from said thermostat operatively connected to said ring, and a source of power for said heating element and thermostat.
